CLAIM

The ornamental design for a pad painter, as shown and described.

DESCRIPTION

FIG. 1 is a top-front perspective view of a pad painter according to a first embodiment of our new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof;

FIG. 8 is a rear-bottom perspective view;

FIG. 9 is a top-front perspective view of a pad painter according to a second embodiment of our new design;

FIG. 10 is a front view thereof;

FIG. 11 is a rear view thereof;

FIG. 12 is a right-side view thereof;

FIG. 13 is a left-side view thereof;

FIG. 14 is a top view thereof;

FIG. 15 is a bottom view thereof;

FIG. 16 is a rear-bottom perspective view;

FIG. 17 is a top-front perspective view of a pad painter according to a third embodiment of our new design;

FIG. 18 is a front view thereof;

FIG. 19 is a rear view thereof;

FIG. 20 is a right-side view thereof;

FIG. 21 is a left-side view thereof;

FIG. 22 is a top view thereof;

FIG. 23 is a bottom view thereof;

FIG. 24 is a rear-bottom perspective view;

FIG. 25 is a top-front perspective view of a pad painter according to a fourth embodiment of our new design;

(Continued)

FIG. 26 is a front view thereof;
FIG. 27 is a rear view thereof;
FIG. 28 is a right-side view thereof;
FIG. 29 is a left-side view thereof;
FIG. 30 is a top view thereof;
FIG. 31 is a bottom view thereof;
FIG. 32 is a rear-bottom perspective view;
FIG. 33 is a top-front perspective view of a pad painter according to a fifth embodiment of our new design;
FIG. 34 is a front view thereof;
FIG. 35 is a rear view thereof;
FIG. 36 is a right-side view thereof;
FIG. 37 is a left-side view thereof;
FIG. 38 is a top view thereof;
FIG. 39 is a bottom view thereof;
FIG. 40 is a rear-bottom perspective view;
FIG. 41 is a top-front perspective view of a pad painter according to a sixth embodiment of our new design;
FIG. 42 is a front view thereof;
FIG. 43 is a rear view thereof;
FIG. 44 is a right-side view thereof;
FIG. 45 is a left-side view thereof;
FIG. 46 is a top view thereof;
FIG. 47 is a bottom view thereof; and,
FIG. 48 is a rear-bottom perspective view.
